(57) **CLAIM**

The ornamental design for signal light as shown and described.

DESCRIPTION

The patent or application file contains at least one drawing executed in color. Copies of this patent or patent application publication with color drawing(s) will be provided by the Office upon request and payment of the necessary fee.

FIG. 1 is an enlarged top front perspective view of a signal light;

FIG. 2 is an enlarged rear bottom perspective view of the signal light;

FIG. 3 is an enlarged bottom view;

FIG. 4 is a side view;

FIG. 5 a rear view;

FIG. 6 top view; and,

FIG. 7 is a bottom view.

The broken lines in FIGS. 1-2 demarcate the boundaries of the enlarged area of the design, and form no part of the claimed design.
